Primary Examiner — Antoine Duval Davis(74) *Attorney, Agent, or Firm* — Wolf, Greenfield & Sacks, P.C.(57) **CLAIM**

The ornamental design for a laser range finder, as shown and described.

DESCRIPTION

FIG. 1 is a top perspective view of a laser range finder showing my new design;

FIG. 2 is a bottom perspective view thereof;

FIG. 3 is a front view thereof;

FIG. 4 is a rear view thereof;

FIG. 5 is a top plan view thereof;

FIG. 6 is a bottom plan view thereof;

FIG. 7 is an enlarged right side view thereof; and,

FIG. 8 is an enlarged left side view thereof.

The broken lines illustrate portions of the laser range finder that form no part of the claimed design. The dash-dotted lines denote the boundary of the claim and form no part of the claimed design.
